ABSTRACT

An extensible passage apparatus which is nested in a cavity formed between the floor of a selected storey and the ceiling of another storey right below the selected storey in a multi-storied building when the passage apparatus is not used and which can extend downwardly to or adjacent to the floor of the lower storey in case of emergency so as to provide an evacuation passage connecting the two stories involved along which occupants in the building can safely and promptly evacuate from the upper storey to the lower storey or vice versa.

The extensible passage apparatus comprises a passage forming means which provides a temporary evacuation exit in a cavity connecting adjacent upper and lower stories in a multi-storied building along which occupants in the building can evacuate from one storey to the other stories in the building. The passage forming means essentially comprises a plurality telescopically connected cylinder elements each having a plate member associated therewith and the cylinder element units are received in the nested position in a cavity formed between the floor of a selected storey and the ceiling of another storey right below the selected storey in a multi-storied building when the passage apparatus is not used. When the passage apparatus is used in case of emergency, for example, the cylinder element units are allowed to slide relative to each other so as to extend downwardly to or adjacent to the floor of the lower storey.

EXTENSIBLE PASSAGE APPARATUS

BACKGROUND OF THE INVENTION

This invention relates to an extensible passage apparatus and more particularly, to an extensible passage apparatus which is received in its nested position between the floor of a selected storey and the ceiling of another storey right below the selected storey in a multi-storied building when the apparatus is not used. When the apparatus is to be used for its intended purpose, for example, in case of emergency, the apparatus is extended to or adjacent the floor of the lower storey so as to provide a temporary evacuation passage along which occupants in the building can evacuate from the upper storey to the lower storey or vice versa and then to a safer place.

Hitherto, various types of emergency evacuation facilities such as emergency staircases, evacuation bags, evacuation chutes, evacuation ladders, slow dropping devices and mats, for example, have been proposed and actually employed. However, most of these prior art emergency evacuation facilities are provided on one side of a building, for example, at areas adjacent the windows and/or outer walls of the building so that occupants in the building can evacuate from within the building to outdoors. Therefore, in case of emergency, occupants working in places remote from the windows in the building could not promptly gain access to the emergency evacuation facilities. Furthermore, it is not easy to handle the prior art emergency evacuation facilities for persons having no or poor knowledge in the use of such facilities. And if occupants in a building have had no or little training in the use of the emergency evacuation facilities, in an emergency, they will consume a lot of valuable time fumbling with the facilities. In case of an emergency, many persons rush to the emergency evacuation facilities all at once thereby causing confusion and thereby rendering it more difficult to evacuate them safely and promptly.

Furthermore, the prior art emergency evacuation facilities generally can handle only a small number of persons and the use of such facilities is especially difficult or impossible for women, children and aged persons. For other people, too, the use of such facilities is not easy and involves various problems including fear, terror and the like. Thus, the prior art emergency evacuation facilities have inevitably imposed a restriction on safe and prompt evacuation of people in cases of emergency.

SUMMARY OF THE INVENTION

Therefore, the present invention is to provide an extensible passage apparatus for use as an emergency evacuation facility which comprises as its essential components a cavity which connects the floor of a selected storey with the ceiling of another storey positioned right below the selected storey in a multi-storied building, a pair of cover members adapted to close and open an opening in the floor of the upper or selected storey and an opening in the ceiling of the lower storey, respectively, and a telescopic passage forming means adapted to be received in a nested position in the cavity when the passage apparatus is not used and extend downwardly to or adjacent to the floor of the lower storey when the passage apparatus is used for its intended purposes.

One feature of the present invention is that the passage forming means comprises a plurality of cylinder elements telescopically connected to each other for relative movement, each having a plate member secured thereto. When the passage forming means is used, the cylinder elements are allowed to slide relative to each other in the downwardly extension direction together with their associated plate members, whereby the cylinder elements and plate members cooperate with each other in providing a temporary evacuation spiral staircase, spiral chute or ladder.

Thus, one principal object of the present invention is to provide an extensible passage apparatus which can be readily operated and enables occupants in a building to move safely and promptly from one storey to another storey in the building in case of an emergency.

Another object of the present invention is to provide an extensible passage apparatus which is received in a nested condition between the floor of a selected storey and the ceiling of another storey right below the selected storey in a multi-storied building when the passage apparatus is not used and when the apparatus is used, the apparatus is allowed to extend downwardly to or adjacent to the floor of the lower storey so that occupants in the building can move from the upper storey to the lower storey or vice versa.

Another object of the present invention is to provide an extensible passage apparatus which, when used for its intended purpose, enables persons to move from a storey where a relatively larger number of person are present per unit time to another storey where a relatively smaller number of persons are present per unit time in a building.

Another object of the present invention is to provide an extensible passage apparatus which can be easily and readily used by women, children and aged people.

Another object of the present invention is to provide an extensible passage apparatus which when used for its intended purpose, enables many persons to evacuate safely and promptly without fear.

Another object of the present invention is to provide an extensible passage apparatus which can be readily installed on a mezzanine floor and veranda as well as within a building.

Another object of the present invention is to provide an extensible passage apparatus which when used in case of an emergency such as a fire, the apparatus effectively protects occupants in a building where the apparatus is installed against smoke, hot air and the like to thereby protect the occupants from suffocation.

Another object of the present invention is to provide an extensible passage apparatus which can be used as a simple temporary staircase on a mezzanine and veranda other than as an emergency evacuation means in case of a fire.

The above and other objects and attendant advantages of the present invention will be more readily apparent to those skilled in the art from reading the following detailed description in conjunction with the accompanying drawings which show preferred embodiments of the invention for illustration purpose only, but not for limiting the scope of the same in any way.

BRIEF DESCRIPTION OF THE DRAWINGS

FIG. 1A is a vertical sectional view of a first embodiment of the present invention showing the embodiment in its nested position between the floor of a selected

storey and the ceiling of another storey right below the selected storey in a multi-storied building;

FIG. 1B is a fragmentary schematic view of cylinder elements employed in said embodiment of FIG. 1A showing the elements in their extended position;

FIG. 2 is a fragmentary perspective view on an enlarged scale showing some of the cylinder elements and their associated footboards in their extended position;

FIG. 3 is a vertical sectional view of a second embodiment of the present invention showing the embodiment in its nested position between the floor of a selected storey and the ceiling of another storey right below the selected storey in a multi-storied building;

FIG. 4 is a vertical sectional view of a third embodiment of the present invention showing the embodiment in its nested position between the floor of a selected storey and the ceiling of another storey right below the selected storey in a multi-storied building;

FIG. 5 is a vertical sectional view showing any one of the embodiments shown in FIGS. 1A to 4 inclusive in its operative or extended position together with hoist means for pulling up the cylinder elements employed in the embodiment;

FIG. 6 is a vertical sectional view of a fourth embodiment of the present invention showing the embodiment in its nested position in the same manner as shown in FIGS. 1A, 2 and 4;

FIG. 7 is a vertical sectional view showing the embodiment of FIG. 6 in its operative or extended position with portions thereof broken away;

FIG. 8 is a top plan view of the staircase formed by the cylinder elements and their associated footboards in the embodiment of FIG. 7 when extended;

FIG. 9 is a vertical sectional view of a fifth embodiment of the present invention showing the embodiment in its nested position in the same manner as shown in FIGS. 1A, 3, 4 and 6 inclusive;

FIG. 10 is a top plan view of the embodiment of FIG. 9 showing the floor cover in its open position with portion thereof broken away;

FIG. 11 is a vertical sectional view of the embodiment of FIG. 9 showing the same in its operative or extended position;

FIG. 12 is a vertical sectional view of a sixth embodiment of the present invention showing the embodiment in its operative or extended position;

FIG. 13 is a vertical sectional view of a seventh embodiment of the present invention showing the embodiment in its operative or extended position in the same manner as shown in FIGS. 1A, 3, 4, 6, 9 and 12 inclusive;

FIG. 14 is a fragmentary perspective view of an enlarged scale showing one of the cylinder elements employed in the embodiment of FIG. 13 together with the chute forming plate associated with the cylinder element;

FIG. 15 is a fragmentary perspective view of portions of the cylinder elements and their associated chute forming plates showing them in their extended position to form a spiral chute;

FIG. 16 is a vertical sectional view of an eighth embodiment of the present invention showing the embodiment in its operative or extended position with portion thereof broken away;

FIG. 17 is a vertical sectional view of a modified passage forming means to be selectively employed in the

embodiments of FIGS. 1A, 3 and 4 showing a portion of the means in the operative or extended position;

FIG. 18 is a vertical sectional view of a modification of the passage forming means of FIG. 17 showing portion thereof in the operative or extended position;

FIG. 19 is a vertical sectional view of a bellowtype sheath member of the present invention showing portion of the same in the operative or extended position; and

FIG. 20 is a vertically sectional view of the embodiment of FIG. 14 having an anti-swing means.

DETAILED DESCRIPTION OF THE INVENTION

The present invention will be now described referring to the accompanying drawings and more particularly, to FIGS. 1A, 1B and 2 thereof which shows a first embodiment of extensible passage apparatus constructed in accordance with the present invention. In FIGS. 1A and 1B, the extensible passage apparatus 50 is shown in its nested position between the floor 30 of an upper storey and the ceiling 40 of a lower storey right below the upper storey in a multi-storied building. The floor 30 of the upper storey is provided with a floor surface opening 31 at both the upper and lower ends and a reinforcing cylindrical framework 32 is snugly fitted in the opening 31 in a coaxial relationship to the latter. The reinforcing framework 32 has at the upper end an integral annular flange 33 extending radially and outwardly from the upper end for covering and reinforcing the area of the floor 30 about the opening 31 and the flange is formed with an annular recess 34 in a coaxial relationship to the framework 32. Similarly, the ceiling 40 of the lower storey is formed with a ceiling surface opening 41 in alignment with the opening 31 in the upper storey floor 30. A reinforcing cylindrical framework 42 is snugly fitted in the opening 41 in a coaxial relationship to the latter and has integral annular flanges 43 and 44 extending radially and outwardly and inwardly from the lower and upper ends of the framework, respectively. The flanges 43 and 44 are integrally connected to each other by the vertical wall of the framework 42.

Since the floor 30 and ceiling 40 are spaced from each other, a cavity 51 connected between the two storeys is defined by a space present between the floor surface opening 31, ceiling surface opening 41, floor 30 and ceiling 40.

When the passage apparatus is not used for its intended purpose, the floor surface opening 31 is closed by a floor side cover 52 which has one end pivotably connected to the flange 33 of the reinforcing cylindrical framework 32 for vertical pivotal movement by means of a hinge 53 which is in turn secured to the flange 33. The other end of the floor side cover 52 is disengageably held in position by a holding member 56 which is in turn pivoted to the flange 33 of the reinforcing framework 32 for lateral pivotal movement in a horizontal direction.

The ceiling opening 41 is closed or opened by a ceiling side cover 54 pivotably connected at one end to the flange 45 of the reinforcing framework 42 for vertical pivotal movement by means of a hinge 55 which is in turn secured to the flange 43.

The other end of the ceiling side cover 54 is operatively connected to an interlocking and releasing mechanism 70 of which description will be made hereinafter. The opening and closing operation of the interlocking

and releasing means 70 is, of course, responsive to the opening and closing operation of the floor side cover 52.

Provided between the floor surface opening 31, floor 30 and ceiling 40 is a telescopic passage forming means 60 which comprises a plurality of telescopically connected cylinder elements 61 (ten cylinder elements are employed in the illustrated embodiment).

The innermost or uppermost cylinder element having the smallest diameter includes a suspension hook 62 of a J-shaped cross section as seen in the vertical direction which engages the inner surface of the reinforcing cylindrical framework 32 with the bent upper end fitted in the annular recess 34 in the flange 33. Each of the cylinder elements 61 has an upwardly bent hook 63 of J-shaped cross section at the lower end and a downwardly bent hook 64 of J-shaped cross section at the upper end and the lower end hook 63 of each cylinder element 61 is adapted to engage the upper end hook 64 of the adjacent outer cylinder element while the upper end hook 64 of each cylinder element is adapted to engage the lower end hook 63 of the adjacent inner cylinder element. Thus, when the passage forming means 60 is allowed to extend downwardly to its predetermined maximum extent as shown with the one-dot chain line in FIG. 1B, the hooks 63 and 64 of the cylinder elements 61 engage each other in the manner as shown in FIG. 2 in which the mating lower and upper hooks 63 and 64 of the adjacent cylinder elements engage each other.

Each of the cylinder elements 61 also has a footboard 65 extending radially and inwardly of the cylinder element at the bottom and the footboard is secured to the inner surface of the associated cylinder element in a cantilever fashion. The footboard 65 of each cylinder element 61 is offset with respect to those of the adjacent cylinder elements. Thus, when the passage forming means 60 is allowed to extend to the position as shown with the one-dot chain line in FIG. 1B, the footboards 65 of the cylinder elements 61 cooperate with each other to provide a spiral staircase. For this purpose, each of the footboards 65 has a substantially triangular shape with the pointed apex or free end 66 extending beyond the center or axis of the associated cylinder element. The apex 66 of the triangular footboard has a circular through hole 67 through which a rope (not shown) which pulls up or retracts the cylinder elements 61 extends.

The innermost cylinder element has the aforementioned interlocking and releasing mechanism 70 attached thereto. The interlocking and releasing mechanism 70 is positioned within the reinforcing framework 42 and so designed that when the floor cover 52 is pivoted from its open position to its closing position with respect to the floor surface opening 31, the ceiling side cover 54 is pivoted from its open position to its closing position with respect to the ceiling surface opening 41 in response to the closing movement of the floor side cover 52. As more clearly shown in FIG. 1A, the interlocking and releasing mechanism 70 comprises a retainer cylinder 71 having a length for limiting the closing position of the covers 52 and 54 and secured to the inner surface of the innermost cylinder element 61, an operation rod 72 extending vertically within and held in the retainer cylinder 71, a spring 73 positioned within the retainer cylinder 71 so as to urge the operation rod 72 upwardly with respect to the retainer cylinder

71, a hole 57 formed in the inner side wall of the ceiling side cover 54, and a retainer 74 pivoted to the inner surface of the ceiling side cover 54 about the periphery of the bore 57 and having one end extending to the operation rod 72 and the other end engaging the inner surface of the cover 54.

The retainer cylinder 71 is open at the top and closed at the bottom by a bottom wall 75 having a hole 76 through which the operation rod 72 extends. Furthermore, a ring 77 is provided with the retainer cylinder 71 adjacent the upper end thereof for guiding the operation rod 72 therethrough. The operation rod 72 has an integral annular flange 78 at the lower end against which the spring 73 abuts. Thus, the spring 73 is positioned about the operation rod 72 between the bottom wall 75 and annular flange 78.

Assuming that a fire occurs in the upper storey with the passage apparatus is in its nested condition as shown in FIG. 1A, the holding member 56 is manually pivoted in the horizontal direction for releasing its holding force on the floor side cover 52 and the cover is then pivoted about the hinge 53 to a substantially vertical position to thereby uncover the floor surface opening 31. As the cover 52 is pivoted in the opening uncovering direction, the upper end of the operation rod 72 is released from the holding force applied thereon by the cover 52 whereupon the spring 73 which is now compressed between the bottom wall 74 and annular flange 78 is allowed to extend to thereby 30 push the operation rod 72 upwardly. Simultaneously, the operation rod 72 is disengaged from the retainer 74 to thereby pivot the ceiling cover 54 about the hinge 55 to a substantially vertical position with respect to the ceiling 40. When the cover 54 is pivoted in the opening uncovering direction as described hereinabove, the cylinder elements 61 slide downwardly relative to each other by their own weight to the one-dot chain position as shown in FIG. 1B to extend the passage forming means 60. In the extended position of the passage forming means 60, the bottom of the lowermost cylinder element of these cylinder elements is positioned slightly spaced above the floor 79 of the lower storey so that occupants in the building can conveniently and safely clear the passage forming means. In this way, the occupants can move from the upper storey to the lower storey by way of the spiral staircase formed by the cylinder elements 61 and their footboards 65. In order that the occupants may readily and safely clear the passage forming means 60, the lowermost and adjacent upper cylinder elements are provided with evacuation windows or doored evacuation exits (not shown), respectively and the evacuation windows in the two particular cylinder elements are adapted to align with each other when the passage forming means 60 extends to its predetermined maximum extent.

FIGS. 3 and 4 show two types of modifications of the passage forming means shown in FIGS. 1A, 1B and 2 and the modified passage forming means are shown with numerals 50a and 50b in FIGS. 3 and 4, respectively. The occupants of the modified passage forming means 50a and 50b are substantially similar to the corresponding components except that the interlocking and releasing mechanism and the lowermost cylinder element is adapted to contact the floor of the lower storey when the associated passage forming means is allowed to extend to its predetermined maximum extent. The other components of the modified passage forming

means are substantially identical with the corresponding components of the afore-mentioned passage forming means in construction and operation and accordingly, the components of the modified passage forming means corresponding to those of the afore-mentioned passage forming means are assigned the same numerals thereto in FIGS. 3 and 4 as those for the parts of the afore-mentioned means and description of these corresponding parts will be eliminated herein for simplification purpose.

In FIG. 3, the interlocking and releasing mechanism 80 associated with the passage forming means 50a comprises as its principal components a suspension rod 81 having the upper end secured to the inner surface of the floor side cover 52 and a locking member 82 secured at the lower end to the inner surface of the ceiling side cover 54 and the upper end engaging the lower end of the suspension rod 81. The locking member 82 may be in the form of a catch, latch or the like member, for example.

The upper end of the suspension rod 81 is pivoted to a pin 84 supported in a block 83 which is in turn welded to the inner surface of the cover 52 and the lower end of the suspension rod has an engaging piece 85 secured thereto to be engaged by the locking member 82 for holding the cover 54 in its closed position.

Assuming that the floor side cover 52 is pivoted about the hinge 53 from the closed position as shown in FIG. 3 to the open position, the engaging piece 85 at the lower end of the suspension rod 81 is disengaged from the locking member 82 whereupon the now closed ceiling side cover 54 is pivoted about the hinge 55 from the closed position to the open position in which the cover 54 is suspended substantially at a vertical position with respect to the ceiling. As the ceiling side cover 54 is opened, the cylinder elements 61 of the passage forming means 60 are allowed to slide downwardly relative to each other by their own weight until the passage forming means 60 extends to its maximum extent in which the lowermost cylinder element 61 contacts the floor of the lower storey (not shown). As mentioned hereinabove, the lowermost and adjacent cylinder elements are also provided with evacuation windows and the like which are adapted to align with each other when the passage forming means has extended to its maximum extent. Furthermore, the lowermost cylinder element has shock absorbing annular rubber members 68 at the under surface thereof which are adapted to absorb shock which may occur when the lowermost cylinder element contacts the lower storey floor.

In FIG. 4, the interlocking and releasing mechanism 90 associated with the passage forming means 50b comprises as its principal components an operation lever 91 pivoted at the upper end to the inner surface of the innermost or uppermost cylinder element 61 and a hook 92 secured to the inner surface of the ceiling side cover 54 for engaging the mating hook-shaped lower end of the operation lever 91. The operation lever 91 includes an upper lever portion 91a extending upwardly from a pivot pin 94 toward the cover 52 and an integral lower lever portion 91b extending downwardly from the pin 94 toward the cover 54 at an angle with respect to the upper lever portion 91a. When the passage forming means 50a is in its nested condition as shown in FIG. 4, the upper lever portion 91a is positioned at an angle with respect to the vertical and the

lower lever portion 91b is positioned substantially vertically. Rotatably supported at the extreme upper end of the operation lever 91 is a roller 95 which is in rolling contact with the inner surface of the cover 52 and a spring 96 extends between the upper lever portion 91a and the inner surface of the uppermost cylinder element 61 for normally urging the lever 91 toward the cylinder element.

Thus, assuming that the cover 52 is pivoted about the hinge 53 from the closed position as shown in FIG. 4 to the open position, the operation lever 91 is pivoted about the pin 94 in the counter-clock direction as seen in FIG. 4 under the action of the spring 95 to thereby disengage the hooked lower end 92 from the mating hook 93 whereupon the now horizontal open cover 54 is allowed to pivot about the hinge 55 to the suspended position to thereby open the ceiling surface opening 41. As the cover 54 is pivoted to the suspended position, the cylinder elements 61 of the passage forming means 60 are allowed to slide downwardly relative to each other until the passage forming means is extended to its predetermined maximum extent whereupon the lowermost cylinder element contacts the floor of the lower storey (not shown). As in the case of the passage forming means 50a of FIG. 3, the lowermost cylinder element in the passage forming means 50b is also provided on the under surface thereof with annular shock absorbing rubber members 68.

FIG. 5 especially shows the details of a hoist mechanism together with the components of the passage apparatus associated with the hoist mechanism and the hoist mechanism is adapted to return or pull up each of the afore-mentioned passage forming means 50, 50a and 50b from its extended position to the nested position as shown in FIGS. 1A, 1B, 3 and 4, respectively. In FIG. 5, the components of the passage apparatus which are not necessary in describing the hoist mechanism are not shown and accordingly, description of such unnecessary components will be eliminated herein.

The hoist mechanism 100 comprises as its principal components a winch drum 102 rotatably mounted on a mounting frame 101 which is in turn fixedly mounted on the inner surface of the uppermost cylinder element 61 and having a handle 103, and a hoist rope 104 having one end fixedly secured to the drum 102 and the other end extending through holes 67 in the footboards 65 of the successive cylinder elements 61 and secured to the hole in the stair forming plate of the lowermost cylinder element. Thus, in order to nestle or store the passage forming means 50, 50a or 50b in the position as shown in FIGS. 1A, 1B, 3 and 4, respectively, after the passage means has been extended as the result of the opening of the floor and ceiling side covers 52 and 54, for example, after an evacuation practice or actual evacuation operation or for nesting or storing after an inspection for function, the winch drum 102 is first rotated by the handle 103 in the direction for winding the hoist rope 104 onto the drum so as to nestle the successive lower cylinder elements 61 in succession. In order to prevent the winch drum 102 from rotating in the rope paying-out direction after the rope has been wound thereon under the weight of the cylinder elements 61, the winch drum is preferably provided with a detent (not shown). Furthermore, the cylinder elements 61 are preferably provided with mating engaging projections (not shown) on the inner surface of the cyl-

inder elements so that when the cylinder elements 61 are pulled up by the hoist mechanism 100, in each two adjacent cylinder elements which slide relative to each other, the upper cylinder element can be positively pulled up by the lower cylinder element. Of course, since the cylinder elements 61 are provided with their respective stair forming plates 65, such projections may be eliminated if desired.

The hoist mechanism 100 is not necessarily provided within the passage forming means 60 as shown in FIG. 5, but may be provided outside of the passage. In such a case, forming means within the winch drum 102 of the hoist mechanism 100 is rotatably mounted on a mounting frame on the under surface of the floor of the upper storey adjacent one side of the uppermost cylinder element 61 and a pulley (not shown) is rotatably mounted on another frame on the under surface of the ceiling 30 of the lower storey on the other side of the uppermost cylinder element in cooperative relationship to the winch drum 102. One end of each of two pull ropes is anchored to the winch drum and the other end of one of the two ropes is anchored to the outside of the lowermost cylinder element while the other end of the other rope is passed over the pulley and anchored to the outside of the lowermost cylinder element. Of course, the anchoring position of the other end of the other rope with respect to the outside of the lowermost cylinder element is preferably symmetrical with the anchoring position of the other end of the one rope.

FIGS. 6 to 8 inclusive show a fourth embodiment of passage apparatus of the present invention and the passage apparatus 50c of these Figures is substantially similar to the afore-mentioned passage apparatus 50, 50a and 50b of FIGS. 1 to 5 inclusive except for the passage forming means. Thus, the remaining components of the passage apparatus corresponding to those of the afore-mentioned embodiments are assigned the same numerals as those assigned to the corresponding components of the afore-mentioned embodiments and description will be made of only the components necessary for understanding the modified passage forming means.

The passage forming means 110 of the passage apparatus 50c is positioned coaxial with a hollow casing 35 defining a cavity 51 which communicate between the floor side opening 31 of the upper storey and the ceiling side opening 41 of the lower storey both of which openings are also coaxial with the cavity 51. In the nested position, the passage forming means 110 is received within the casing 35.

The passage forming means 110 comprises as its principal components eight cylinder elements 112 which are telescopically connected together for slidable movement relative to each other and adapted to form a support column 113 when the cylinder elements are allowed to extend to their predetermined maximum extent footboards 113 extending radially and outwardly from their associated cylinder elements adjacent the bottoms thereof in an offset relationship to each other, suspension members 114 anchored at the lower ends to their respectively associated footboards 113 at suitable points of the footboards for suspending the cylinder element and plate units when they extend. The suspension members may be in the form of a chain or rope.

The outermost or uppermost cylinder element of the plural support column forming cylinder elements 112 is secured to the inner surface of the casing 35 by

means of a support arm 115 extending horizontally between the casing and uppermost cylinder element.

The mutual relationship between the eight cylinder elements will be understood from the showing of FIGS. 6 and 7. That is, in each two adjacent upper and lower cylinder elements, the lower cylinder element is telescoped within the upper cylinder element for relative sliding movement therebetween. Thus, it will be noted that the uppermost or outermost cylinder element has the largest diameter, the successive lower cylinder elements have successively reduced diameters and the lowermost cylinder element has the smallest diameter. In use, the cylinder elements 112 are allowed to extend downwardly to their predetermined maximum extent by their own weight so as to form the support column 111 for supporting the passage apparatus. For the purpose, the cylinder elements are preferably formed with communication holes (not shown) which open to the atmosphere. The upper ends of the suspension members 114 are anchored to the inner surface of the top edge of casing 35.

Now assuming that the passage apparatus 50c is in its nested position as shown in FIG. 6 and the occupants are expected to evacuate from the upper storey to the lower storey, the floor side cover 52 is first manually pivoted to the open position. In response to the pivotal movement of the cover 52 in the opening direction, the interlocking and releasing mechanism (not shown) similar to those for the embodiments shown in FIGS. 1A, 1B, 3 and 4 is actuated to pivot the ceiling side cover 54 in the opening direction. As a result, the cylinder elements 112 are allowed to slide downwardly relative to each other by their own weight until the lower end of the lowermost cylinder element contacts the floor 79 of the lower storey to thereby form the support column 111 for the passage apparatus. In the extended position of the cylinder elements 112, the footboards 113 associated with the cylinder elements form a spiral staircase about the support column 111. Thus, the occupants of the building can move from the upper storey to the lower storey via the passage forming means 110.

FIGS. 9 to 11 inclusive show a fifth embodiment of passage apparatus of the invention and the passage apparatus 50d is shown in its nested or inoperative position in a cavity 51a defined by a horizontal partition well member 39 integrally formed with the floor of a selected storey and the ceiling of a storey right below the selected or upper storey in FIG. 9. The passage apparatus 50d is substantially identical with the afore-mentioned embodiment of FIGS. 6 to 8 inclusive except that the cavity 51a including the floor side opening and the ceiling side opening has a rectangular shape in cross-section and accordingly, the floor side cover 52a and ceiling side cover 54a also have the corresponding rectangular shape in cross-section. Furthermore, the passage apparatus of FIGS. 9 to 11 inclusive are different from the embodiment of FIGS. 6 to 8 inclusive in the attaching position of the footboards on the cylinder elements of the passage forming means and the mounting position of the passage forming means within the cavity. The construction and operation of the remaining components of the passage apparatus 50c are identical with the corresponding components of the embodiments of FIGS. 1A to 8 inclusive and accordingly, only such components necessary for understanding the embodiment of FIGS. 9 to 11 inclusive are shown and will be described herein. Thus, the components of the

passage apparatus 50d corresponding to those of the embodiments 50, 50a, 50b and 50c are assigned the same numerals as those assigned to the corresponding components of the afore-mentioned embodiments. The modified passage forming means of the passage apparatus 50d is more particularly shown in FIGS. 9 to 11 inclusive and details of the construction and operation of the modified passage forming means will be in detail described hereinbelow.

As shown in FIGS. 9 and 10, the passage forming means 120 of the passage apparatus 50d is secured to one of the shorter side walls of a rectangular cross-section cavity 51a by means of four set bolts 125 and adapted to be received in its nested position between the floor side cover 52a and ceiling side cover 54a.

The arrangement of the footboards on the associated cylinder elements in the passage forming means 120 are different from that of the footboards 113 on the associated cylinder elements 112 in the passage forming means 110 of FIGS. 6 to 8 inclusive. That is, in the passage forming means 120, the support column 121 consists of seven cylinder elements which are telescoped one within another for relatively slidable movement to each other as in the case of the cylinder elements 112 and the footboards 123 of the successive cylinder elements 122 are alternately staggered. That is, the footboards 123 of each cylinder element 122 extends laterally from the outer surface of the cylinder element in the direction opposite to the corresponding components of the adjacent cylinder elements to thereby form a ladder in cooperation with the adjacent cylinder element footboards 123. The mounting of the passage forming means 120 on the one shorter side wall of the cavity 51a is effected by means of four bolts 125 passing through a mounting framework 124 integrally welded to the uppermost cylinder element.

Assuming that the passage apparatus 50d is in its nested position as shown in FIG. 9 and the occupants in the building are expected to move from the upper storey to the lower storey, the floor side cover 52a is first manually pivoted in the opening direction and in response to the pivotal movement of the cover 52a, the interlocking and releasing mechanism (not shown) similar to the mechanisms 70, 80 and 90 in the embodiments of FIGS. 1A, 1B, 3 and 4 is actuated to pivot the ceiling side cover 54a in the opening direction. As a result, the cylinder elements 122 are allowed to slide downwardly relative to each other by their own weight until the lower end of the lowermost cylinder element contacts the floor of the lower storey whereupon the footboards 123 associated with the cylinder elements cooperate with in forming the ladder. Thus, the occupants in the building can now move from the upper storey to the lower storey or vice versa.

FIG. 12 shows a sixth embodiment of passage apparatus of the invention in its operative or extended position. As in the case of the embodiment of FIGS. 9 to 11 inclusive, when not used, the passage apparatus 50e is received in its nested position within the cavity 51a defined by a horizontal partition wall member 39 integrally formed with the floor of a selected or upper storey and the ceiling of another storey right below the selected storey in a multi-storied building. The passage apparatus 50e comprises a further modification of the passage forming means 120 employed in the passage apparatus 50d of FIGS. 9 to 11 inclusive. The remaining components of the passage apparatus 50e are simi-

lar to or identical with the corresponding components of the passage apparatus of FIGS. 9 to 11 inclusive and therefore, this construction and operation of only portions of the corresponding components necessary for understanding the embodiment of FIG. 12 are shown and will be described hereinbelow. The components of the passage apparatus 50e corresponding to those of the embodiment of FIGS. 9 to 11 inclusive are assigned thereto the same numerals as those assigned to the corresponding components of the embodiment of FIGS. 9 to 11.

Details of the construction and operation of the modified passage forming means 130 of the passage apparatus 50e are shown and will be described hereinbelow.

As shown in FIG. 12, the passage forming means 130 is secured in the upper portion to one shorter side wall of the cavity 51a of rectangular in cross-section by means of set bolts 136. When not used, the passage forming means 130 is received in its nested position in the cavity 51a between the floor side cover 52a of the upper storey and the ceiling side cover 54a of the lower storey. The passage forming means 130 comprises a pair of identical cylinder element units 133, 133 arranged in parallel to each other and each unit includes seven different diameter cylinder elements telescoped one within another for slidable movement relative to each other to form a support column 132 when extended downwardly or in its operative position. The cylinder elements 133 in the pair of cylinder element units have footboards 134 and 145 secured thereto, respectively which extend from the inner sides of the cylinder elements radially and inwardly toward each other to form a stair case when the cylinder element units are extended to their maximum extent. For this purpose, the footboards 134 of the cylinder elements 133 in one cylinder element unit are positioned in the same height as the mating footboards 135 of the respectively opposite cylinder elements 133 in the other cylinder element unit. As shown in FIG. 12, when the passage apparatus 50e is in its operative position or the cylinder element units are in their extended position, the lower ends of the support columns 131 and 132 formed by the cylinder element units 133, 133 or the lower ends of the lowermost cylinder elements 133 in the pair of cylinder element units contact the floor 79 of the lower storey. Since the manipulation manner of the passage apparatus 50e in which the apparatus is shifted from the nested position to the operative position or vice versa is identical with that described in connection with the embodiment of FIGS. 9 to 11 inclusive, the manipulation manner of the apparatus 50e will be eliminated herein.

FIGS. 13 to 15 inclusive show a seventh embodiment of passage apparatus of the invention and the passage apparatus 50f of these Figures is a modification of the embodiments of FIGS. 50, 50a and 50b of FIGS. 1A to 4 inclusive and when in its nested position, the apparatus 50f is adapted to be received in a cavity 51 defined by a horizontal partition wall member 39 integrally formed with the floor of a selected storey and the ceiling of another storey right below the selected storey in a multi-storied building. The passage apparatus 50f comprises a modification of the passage forming means 60 employed in the passage apparatus 50, 50a and 50b of FIGS. 1 to 4 inclusive and the modified passage forming means 140 of the passage apparatus may comprise the components constituting the passage forming

means of the apparatus 50, 50a and 50b shown in FIGS. 1 to 4 and therefore, the components of the modified passage means 140 are only schematically shown and description will be made only to the extent necessary for understanding the construction and operation of the passage forming means 140. Thus, the components of the passage apparatus 50f forming means 140 corresponding to those of the passage apparatus are assigned to the same numerals as those assigned to the corresponding components of the afore-mentioned embodiments.

Details of the construction and operation of the modified passage forming means 140 are shown and will be described hereinbelow.

The passage forming means 140 comprises four cylinder elements 141 telescoped one within another for slidable movement relative to each other as seen in FIGS. 13 to 15 inclusive. The lowest or smallest diameter cylinder element of cylinder elements 141 has an inner diameter sufficient for a person to pass freely through the cylinder element. In each two adjacent cylinder elements, the lower cylinder element has a diameter somewhat smaller than that of the upper cylinder element. Each cylinder element has an integral annular hook 64 of reversed J-shape in cross-section at the upper peripheral edge and the lower peripheral edge of each cylinder element is integrally formed with a matching J-shape cross-section annular hook 63. Thus, the cylinder elements are allowed to slidably move each other and when the passage forming means is extended to its predetermined maximum extent, the hooks 63 at the lower peripheral edges of the lower cylinder elements engage the hooks 64 at the upper peripheral edges of the upper cylinder elements to thereby limit the relative slidable movement of the cylinder elements. The hook 64 at the upper peripheral edge of the uppermost cylinder element engages and suspends from a hook 142 formed in the inner surface of the cavity forming partition wall member 39 integrally formed with the floor of the upper storey and the ceiling of the lower storey and thus, all the four cylinder elements 141 are suspended in the cavity 51 when the passage apparatus 50f is in its inoperative position.

Each of the cylinder elements 141 has a downwardly inclined chute plate 143 of a suitable radius of curvature within the interior thereof. As more clearly shown in FIG. 14, the chute plate 143 is pivotably supported at the upper end on a pivot pin 144 cantilevered on the inner surface of the associated cylinder element adjacent the upper edge of the latter. The chute plates 143 of the successive cylinder elements 141 are so offsetted relative to each other that when the passage forming means 140 is extended to its maximum extent, the upper end of each lower chute plate 143 contacts the lower end of the adjacent upper chute plate 143 to form a downward extension of the upper chute plate to thereby form a spiral chute (see FIG. 15). Since the chute plates 143 are pivotable about their associated cantilevered pivot pins 144, the plates will not obstruct the upward slidable movement of the successive lower cylinder elements within the successive upper cylinder elements.

The passage forming means 140 has a winch 145 so as to pull up each cylinder element 141 into its nested position.

This winch 145 is supported at one end portion of supporting arm 148 which is fixed at the other end por-

tion thereof the inner surface of to the uppermost cylinder element 141.

The winch 145 involves a rope 146 so as to pull up the cylinder elements 141.

5 The rope 146 is fixed at one end of its length to the winch 145 and the other end of its on the lowermost cylinder element 141.

Further, the rope 146 is positioned inside the telescopic gripping rod 149.

10 The telescopic gripping rod 149 comprises four telescopically connected cylinder elements 149a and the uppermost cylinder element 149a is fixed on the supporting arm 148.

Each cylinder element 149a has a slender out-side 15 diameter and both ends of the cylinder elements 149a are opened.

When the passage forming means 140 and accordingly, the cylinder elements 141 constituting the means are pulled up into the nested position within the cavity

20 51, the floor and ceiling side covers 52 and 54 close the floor and ceiling surface openings 31 and 41, respectively and are locked in the closed position by the interlocking and releasing mechanism (not shown) similar to the corresponding mechanism employed in each of

25 the embodiments shown in FIGS. 1A to 4, respectively. Thus, when the passage apparatus 50f of FIGS. 13 to 15 inclusive is operated for evacuating the occupants in the building from the upper storey to the lower storey, for example, the floor side cover 52 is first manu-

30 ally pivoted in the opening direction. In response to the pivotal movement of the floor side cover in the opening direction, the interlocking and releasing mechanism is actuated for releasing operation to pivot the ceiling side cover 54 in the opening direction whereupon the

35 cylinder elements 141 of the passage forming means 140 are allowed to slide downwardly relative to each other until the lower end of the lowermost cylinder element contacts the floor 79 of the lower storey. In the extended position of the passage forming means 140,

40 the chute plates 143 in the successive cylinder elements 141 form the spiral chute along which the occupants can slide from the upper storey to the lower storey. As in the foregoing embodiments, the lowermost cylinder element is provided with an evacuation window or

45 doored evacuation exit (not shown).

FIG. 16 shows an eighth embodiment of passage apparatus of the invention and the passage apparatus of this FIG. 16 is a modification of the passage apparatus 50f of FIGS. 13 to 15 inclusive. The passage apparatus

50 50g of FIG. 16 is substantially identical with the embodiment of FIGS. 13 to 15 inclusive except for the passage forming means and the remaining components of the passage apparatus of FIG. 16 may be selectively employed from the corresponding components of the foregoing embodiments as desired. Thus, the selectively employed components are only schematically shown and the construction and operation of these components will be briefly described only to the extent necessary for understanding the passage apparatus of

55 FIG. 16. Therefore, the components of the passage apparatus of FIG. 16 corresponding to those of the foregoing embodiments 50, 50a, 50b, 50c, 50d, 50e and 50f are assigned the same numerals as those of the corresponding components of the foregoing embodiments.

60 And the modified passage forming means of the passage apparatus 50g is particularly shown and will be described in detail hereinbelow.

65

When not used, the passage apparatus 50g is received in its nested position within the cavity 51 defined by a partition wall member integrally formed with the floor 30 of a selected storey and the ceiling 40 of another storey right below the selected storey in a multi-storied building. The passage forming means 150 of the passage apparatus 50g comprises an expandible outer cylinder unit 151 including a plurality of cylinder elements 61 telescoped one within another for relative slidable movement to each other (four cylinder elements are shown in FIG. 16) as in the case of the embodiments of FIGS. 13 to 15 inclusive. The passage forming means 150 further comprises an inner cylinder element unit formed of a plurality of cylinder elements telescopically connected one within another for relative slidable movement to each other as described in connection with the embodiment of FIGS. 6 to 8 inclusive and adapted to form a support column 121 when they are allowed to extend to a predetermined maximum extent, and resilient chute plates 153 extend about the associated inner cylinder elements sloping downwardly and adapted to form a spiral chute in cooperation with the thus formed support column 121 when the inner cylinder element unit extends. The inner cylinder element unit is coaxially disposed within the outer cylinder element unit 151. Also, the chute plates 153 comprise the chute plate 143 shown in FIGS. 13 to 15. In that case, the pivot pins 144 is fixed on the inner surface of the cylinder element 61.

Since the passage apparatus 50g is operated substantially in the same manner as described in connection with the embodiment 50f of FIGS. 13 to 15 inclusive, description of the operation of the embodiment of FIG. 16 will be eliminated herein.

FIG. 17 shows a modified passage forming means which can be optionally employed in the aforementioned passage apparatus 50, 50a, 50b, 50c, 50d, 50e, 50f and 50g. The passage forming means 160 of FIG. 17 is adapted to be nested within the cavity 51 extending through the floor of a selected storey and the ceiling of another storey right below the selected storey in a multi-storied building.

The passage forming means 160 comprises an elastically extensible pleated guide cylinder 161 which can be resiliently folded to reduce its length and extended for allowing a person to pass through, and a plurality of footboards 165 secured to and extending radially and inwardly from the inner surface of the cylinder 161 in an offset relation to each other to form a spiral staircase within the cylinder 161 when the cylinder is allowed to extend.

The guide cylinder 161 includes a cylindrical member 162 adapted to fold to reduce its length, a plurality of frame rings 163 positioned about the cylindrical member 162 in an equal spaced relationship in the length of the cylindrical member and a plurality of resilient rings 164 formed of a resilient material each secured to the inner surface of the cylindrical member between adjacent rings 163 for folding portions of the cylindrical member between the rings 163.

When not subjected to any external force, the diameter of the rings 164 is smaller than that of the frame rings 163 and depends upon a desired folding amount of portions of the cylindrical member 162 between the frame rings. Furthermore, the footboards 165 are integrally secured to the inner surface of the guide cylinder 161 in such an offset relation that the plates form a spi-

ral staircase when the guide cylinder is allowed to extend to its predetermined maximum extent.

With the above construction and arrangement of the passage forming means 160, when the passage apparatus 50g is not used, the guide cylinder 161 is received in its nestled position within the cavity communicating between the floor of the upper storey and the ceiling of the lower storey of the building (not shown) in which the portions of the cylindrical member 162 between the frame rings 163 are folded inwardly toward the diameter of the frame rings 163 due to the elasticity of the rings 164. When the passage apparatus is used, the cylindrical member 162 which is secured at the upper end to the inner surface of the cavity is allowed to extend downwardly to the floor of the lower storey principally by the weight of the cylindrical member 162 and frame rings 163 to thereby form a spiral staircase within the cylindrical member 162. In the extended position of the cylindrical member 162, since the weight of the cylindrical member readily overcomes the resiliency of the folding rings 164, the diameter of the folding ring 164 extends substantially to the diameter of the cylindrical member 162.

FIG. 18 shows a modification of the passage forming means 160 of FIG. 17 and the passage forming means 170 of FIG. 18 comprises a guide frame cylinder unit 171 foldable to reduce its length and extendable for allowing a person to pass through the cylinder unit at one time, and a plurality of footboards 176 secured to and extending radially and inwardly from the inner surface of the guide framework cylinder unit in an offset relationship so as to form a spiral staircase therein.

The guide framework cylinder 171 includes eight frame rings 172 positioned along the periphery of the cylinder 171 in an equal spaced relationship in the longitudinal direction thereof, and at least three sets of foldable connector rods 173 for connecting each two adjacent frame rings 172 at a predetermined spaced relationship in the longitudinal direction of the cylinder 171.

Each of the connector rods 173 comprises a pair of connector elements 174 and 175. The connector element 174 has one end pivoted to the adjacent lower frame ring 172 and the connector element has one end pivoted to the adjacent upper ring 172. The other ends of the connector elements 174 and 175 are pivotably connected to each other.

Each of the afore-mentioned footboards 176 is integrally attached to the inner surface of the associated frame ring 172 in such an offset relationship that when the framework cylinder unit 171 is allowed to extend in the axial direction, the footboards cooperate with each other in forming a spiral staircase.

With the above construction and arrangement of the passage forming means 170, the passage formed may fold upon itself or extend downwardly by its own weight.

FIG. 19 shows a further modified passage forming means employing a bellows-type sheath member constructed in accordance with the present invention.

The passage forming means 180 of FIG. 19 is adapted to be positioned in its nested position between the floor 30 of a selected storey and the ceiling 40 of another storey right below the selected or upper storey in a multi-storied building when the passage forming means is not used and extends downwardly to thereby allow occupants in the building to evacuate from the upper sto-

rey to the lower storey when the passage forming means is used. An upright cylinder 181 is fitted and extends between the opening in the floor surface opening 31 and the ceiling surface opening 41. A floor side cover 52 is pivoted to the upper edge 182 of the cylinder 181 by beams of a hinge 53 and a ceiling side cover 54 is pivoted to the lower edge 183 of the cylinder by means of a hinge 55.

A rope support device 184 is mounted on the inner surface of the upright cylinder 181 for supporting a guide rope 189 and includes an open-end retainer cylinder 185 secured to the inner surface of the upright cylinder 181 and a retainer rod 186 telescoped in the retainer cylinder 185 for slidable and rotational movement therein. The retainer rod 186 is bent horizontally at the upper end portion to provide a horizontal retainer arm 187 to which one end of a guide rope 189 is attached. The lower end of the retainer rod 186 has an engaging piece (not shown) similar to the engaging piece 85 in the interlocking and releasing mechanism as shown in FIG. 3. The engaging piece at the lower end of the retainer rod 186 is adapted to engage and disengage from a locking member (not shown) similar to the locking member 82 in the interlocking and releasing mechanism as shown in FIG. 3 and secured to the inner surface of the ceiling side cover 54. Furthermore, the retainer rod 186 has in an intermediate position between the opposite ends thereof a stopper 188 which serves to hold the retainer rod in position when the retainer rod has been extended from the retainer cylinder 185 by a predetermined distance.

The upright cylinder 181 has a plurality of suspension arm members 191 extending radially and inwardly from the inner surface of the upright cylinder toward the axis thereof in a position adjacent the ceiling of the lower storey and a bellows-type sheath member 190 is anchored at the upper end to and depends from the suspension arm members 191. The bellows-type sheath member 190 surrounds a guide rope 189 therein and has a length sufficient to extend from the ceiling 40 to the floor of the lower storey when the passage forming means is in its operative position. When the aforementioned passage forming means 180 in its nested position between the floor of the upper storey and the ceiling of the lower storey is operated for its intended purpose, the floor side cover 52 is first pivoted in the opening direction and then, the retainer rod 185 is extended upwardly from the retainer cylinder 185 whereupon the retainer rod is held in position by the stopper 188 as shown in FIG. 19. As the retainer rod 186 is extended in the manner mentioned just above, the engaging piece at the lower end of the retainer rod 186 disengages from the locking member whereupon the ceiling side cover 54 is pivoted in the opening direction whereby the guide rope 189 and bellows-type sheath member 190 are allowed to extend to the floor 79 of the lower storey. In this way, the occupants in the building can evacuate from the upper storey to the lower storey. In case of fire occurrence, the bellows-type sheath member 190 can effectively protect the evacuating occupants from suffocation which may be otherwise probable due to smoke and hot air in the event of fire. The bellows-type sheath member 190 described just above can be optionally employed in the afore-mentioned various passage forming means as desired. Furthermore, it may, of course, occur to those skilled in the art that various modifications and changes

may be made on the afore-mentioned sheath member 190. In each embodiment of the invention shown in FIGS. 1A, 1B, 2, 3, 4, 5, 13, 14, 15 and 16, each cylinder element has the function of the sheath member 190.

In the passage forming means described in connection with FIG. 1A to 4 inclusive, the footboards are so secured to the inner surface of the associated cylinder elements that when the cylinder elements are allowed to slidably extend to a predetermined maximum extent, the footboards form a spiral staircase. However, such footboards may be secured to the associated cylinder elements so as to form a ladder when the cylinder elements are allowed to fully extend.

Furthermore, in order to prevent the cylinder elements, the support columns formed by such cylinder elements and/or guide rope from swinging while they are being employed, an anti-swing means 200 (see FIG. 20) is preferably provided on the cylinder elements 20 which contact the floor or at the free end of the guide rope.

FIG. 20 shows the fifth embodiment of the invention having the anti-swing means 200.

The anti-swing means 200 is formed as the suction member and is fixed on the outermost end of the lowermost cylinder element 122.

Accordingly, if the passage apparatus is operated and extended and the lowermost cylinder element 122 reaches on the floor 79 of the lower storey, the suction member 200 is attached to the floor 79 and at the same time the support column 121 is fixed on the floor 79. Such anti-swing means may be in the form of a suction member or magnet. When the anti-swing means in the form of a magnet is employed, it is necessary that the surface of the floor is provided with a member formed of a material adapted to be attracted by the magnet.

What is claimed is:

1. A passage apparatus adapted to be contained in a passageway between the floor of one story of a building and the ceiling of the story immediately therebelow for passage between the two stories, said apparatus comprising:

a first cover for covering the opening in the floor of the upper story leading to said passageway;

a second cover for covering the other end of said passageway opening through the ceiling of the lower story in line with said first cover covering the opening in the floor above;

and extensible passage means between said covers comprised of a single set of a plurality of cylindrical elements telescoped one within the other slidably movable relative to each other for telescoping downward from a nested position between said covers to the floor below and plate members attached to and projecting from the wall of each cylindrical element whereby physical movement up and down said passage means is facilitated.

2. A passage apparatus as claimed in claim 1, wherein the innermost cylindrical element of said plurality of cylindrical elements in the extensible passage means has an inner diameter sufficient to allow a single person to pass therethrough, and wherein said plate members are in the form of footboards secured to the inner wall of the respective cylindrical elements, the plate member of each cylindrical element being offset with respect to the plate members of the adjacent cylindrical elements, for forming a spiral staircase when the exten-

sible passage means extends downwardly to its predetermined maximum extent.

3. A passage apparatus as claimed in claim 1 wherein the cylindrical elements, when fully extended, cooperate with each other to form a support column for said passage apparatus and wherein said plate members are in the form of footboards secured to the outer wall of said cylindrical elements, the plate member of each cylindrical element being offset with respect to the plate members of the adjacent cylinder elements, for forming a spiral staircase when the passage forming means extends downwardly to its predetermined maximum extent.

4. A passage apparatus as claimed in claim 1, wherein the innermost cylindrical element of said telescopically connected cylindrical elements in the extensible passage means has an inner diameter sufficient to allow a single person to pass therethrough, and wherein said plate members are in the form of footboards secured to the inner wall of the cylindrical elements, the plate member of each cylindrical element being offset with respect to the plate members of the adjacent cylindrical elements for forming a ladder when said passage forming means extends downwardly.

5. A passage apparatus as claimed in claim 1 wherein said cylindrical elements of the extensible passage means have diameters such that when the passage means extends downwardly, the cylindrical elements cooperate with each other to form a support column for said passage apparatus, and wherein said plate members are in the form of footboards secured to the outer wall of said cylindrical elements in such a manner that when said passage forming means extends downwardly the plate members cooperate with each other to provide alternate left and right footboards, thereby forming a ladder.

6. A passage apparatus as claimed in claim 1, wherein the innermost cylindrical element of said telescopically connected cylindrical elements in the extensible passage means has an inner diameter sufficient to allow a single person to pass therethrough, and wherein said plate members are in the form of chute plates secured

to the inner wall of the cylindrical elements with the plate member of each cylindrical element being offset with respect to the plate members of the adjacent cylindrical elements for forming a spiral chute when said passage means extends downwardly,

7. A passage apparatus as claimed in claim 1, wherein the cylindrical elements, when fully extended, cooperate with each other to form a support column for said passage apparatus;

said plate members are the form of chute plates secured to the outer wall of said set of cylindrical elements, with the plate member of each cylindrical element being offset with respect to the plate members of the adjacent cylindrical elements, thereby forming a spiral chute when said extensible passage means extends downwardly; and said apparatus further comprised of

a second set of telescopically connected cylindrical elements coaxial with and surrounding said first-mentioned set of cylindrical elements for forming an extensible outer cylinder around said first-mentioned set of cylindrical elements and having a radius sufficiently large enough to allow a single person to pass between said second set of cylindrical elements and said first-mentioned set of cylindrical elements when both sets of cylindrical elements are extended.

8. A passage apparatus as claimed in claim 1, further comprising a protective cylinder of resilient and fire-resistant material for surrounding the extensible passage means in a coaxially spaced relationship therewith, thereby protecting persons passing along the passage means from smoke and hot air when said passage apparatus is in its operative position.

9. A passage apparatus as claimed in claim 1, in which said extensible passage means is further comprised of an anti-swing means located at the lower end thereof for contacting the floor of the lower story or the ground and for holding the passage means in position when the passage means is extended downwardly.
